United States Patent Office

Des. 183,458
Patented Sept. 2, 1958

183,458

NECKTIE

Samuel Klaus, Brooklyn, N. Y.

Application May 28, 1956, Serial No. 41,677

Term of patent 7 years

(Cl. D3—16)

Fig. 1 is a fragmentary top plan view;
Fig. 2 is a fragmentary side elevational view; and
Fig. 3 is a top plan view on smaller scale of a necktie showing my new design.

I claim:

The ornamental design for a necktie, as shown.
